UNITED STATES PATENT OFFICE.

RALPH C. BROWNE, OF SALEM, MASSACHUSETTS, ASSIGNOR, BY MESNE ASSIGNMENTS,
TO BROWNE APPARATUS COMPANY, OF SALEM, MASSACHUSETTS, A CORPORATION
OF MASSACHUSETTS.

DETECTOR FOR WIRELESS TELEGRAPHY.

1,102,184.

Specification of Letters Patent. Patented June 30, 1914.

Application filed August 15, 1907. Serial No. 388,577.

To all whom it may concern:

Be it known that I, RALPH C. BROWNE, of Salem, in the county of Essex and State of Massachusetts, have invented certain new and useful Improvements in Detectors for Wireless Telegraphy, of which the following is a specification.

This invention is particularly related to that part of a wireless telegraph system known as the detector, and has for its purpose to increase the general efficiency of such devices, both as regards sensitiveness and ease of adjustment.

I have found that, to insure the best results in detectors of the type to which this invention relates, materials of comparatively high thermal electromotive force should be employed in adjustable contact with each other; that the point of contact should be small in order to increase its resistance over the rest of the circuit, so as to centralize the greatest portion of the energy at that point in the form of heat; and that the remainder of the circuit should have as low a resistance as possible. I have found that this result may be secured by utilizing, as one of the conducting materials, crystallized oxid of zinc (said oxid of zinc containing preferably traces of iron or other metallic salts in order to lower its resistance and increase its thermal electrical properties). This crystallized zinc oxid should preferably be in a wedge-shaped form, so that a thin knife edge of the material may be brought into contact with a similar shaped piece of the same material, or preferably some material differing either in regard to its resistance, composition, crystallization or other properties. I have found that excellent results may be obtained by using the natural mineral product known as zinkite (red oxid of zinc) as the active element, and copper pyrites or chalcopyrite as the opposite element. Both of said elements are preferably mounted in suitable conducting metallic holders, with the thin portions in contact with each other, and their bases or thicker portions in good electrical contact with their holders.

The drawing illustrates diagrammatically the receiving end of a wireless telegraph system and shows the general arrangement of the detector as I prefer to build it.

A and B indicate two suitable metal posts

affixed to the insulating base C, which also carries the binding posts D D' to receive the circuit terminals. Through the posts A and B project the holders E and F which may be adjusted toward and from each other and held after adjustment by set screws. One of them is rotatably adjustable, being rotatably mounted in a sleeve S' and having a milled head S. One of the holders, such as that at F, is under the tension of a spring G, which is conveniently located in the sleeve S', whereby a slight spring pressure is maintained by one of the terminals against the other.

H represents a wedge-shaped terminal consisting of a crystal of zinkite, made by chipping off a fragment of the ore. This is held by its thickest portion in the holder E and presents a thin edge to the opposing terminal I, which may consist of a fragment or piece of copper pyrites secured in the holder F. Just what action the copper pyrites plays in the operation of the instrument, it is hard to state, as many other materials will work well with the oxid of zinc, such as zinc blend, iron, bismuth, antimony, zinc, brass, copper, lead, etc.

The copper pyrites however, I prefer to use as it is readily chipped into suitable thin sections having sharp edges, and the thin edges have a high resistance. I am inclined to think that the ore is, to a certain extent, broken up under the action of the heating of the point of contact, and that a chemical action takes place with the opposing element, (though I have not been able to clearly demonstrate the latter) thus giving rise to additional energy in the receiver circuit.

Having thus briefly described my invention for the purpose of explanation and not of limitation, what I claim is:

1. A device for detecting the presence of electrical currents, comprising a terminal consisting of an ore containing oxid of zinc, and an opposing terminal consisting of an ore containing copper.

2. A device for detecting the presence of electrical currents, comprising terminals consisting of zinkite and copper pyrites respectively.

3. An oscillation receiver, which comprises a fragment of chalcopyrite in electrical contact with a substantially rough, un-

polished fracture surface of the electrically conducting solid, the mineral red oxid of zinc substantially as described.

4. An oscillation receiver, which comprises
5 the substances zinkite and chalcopyrite in
electrical contact with each other substantially as described.

In testimony whereof I have affixed my signature, in presence of two witnesses.

RALPH C. BROWNE.
